UNITED STATES PATENT OFFICE.

CLARENCE E. BAUMER AND JOHN CORREY, OF TROY, OHIO.

TRACK INSTRUMENT.

1,114,436.

Specification of Letters Patent.

Patented Oct. 20, 1914.

Application filed February 26, 1914. Serial No. 821,284.

To all whom it may concern:

Be it known that we, CLARENCE E. BAUMER and JOHN CORREY, citizens of the United States, residing at Troy, in the county of Miami and State of Ohio, have invented certain new and useful Improvements in Track Instruments, of which the following is a specification, reference being had therein to the accompanying drawing.

10 This invention relates to a track instrument, and the principal object of the same is the provision of a device which may be easily swung to an operative position so as to engage the valve operating mechanism of an engine.

15 Another object of this invention is the production of a track instrument having an efficient locking means which is adapted to hold the track instrument in an operative position for engagement by the valve controlled mechanism of the engine.

With these and other objects in view, this invention consists of certain novel combinations, constructions and arrangements of 20 parts as will be hereinafter fully described and claimed.

In the accompanying drawings—Figure 1 is a perspective view of the track instrument. Fig. 2 is a sectional view through a 25 portion of the track showing the track instrument carried thereby. Fig. 3 is a detailed perspective view of one of the plates showing the same mounted upon the operating shaft. Fig. 4 is a fragmentary view of 30 an operating lever which is formed upon the shaft. Fig. 5 is a section taken on the line 35 5—5 of Fig. 3. Fig. 6 is a detailed perspective view of the locking mechanism which is adapted to hold the track instrument in an 40 operative position.

Referring to the accompanying drawings by numerals 1 and 2 indicates the usual rails which are supported upon the ties 3 and are held in position by the usual spikes 4. Interposed between a plurality of the ties 3 upon the under side of the flange of the rails 45 1 and 2 are provided the supporting journals 5. These journals 5 may be held in fixed engagement with the rails by any suitable means such as bolts indicated at 6 and are provided with the enlarged hollow body 7 for carrying the operating shaft 8. This operating shaft extends transversely across the track and carries the sleeve 9 of a plate 50 10, this sleeve being held in a set position by means of the set-screw 11. By the adjust-

ment of this set-screw 11 the sleeve 9 may be moved along the operating shaft 8 so as to allow the plate 10 to be positioned in any desired position along the shaft 8 for engagement by the valve operating mechanism of the engine.

For the purpose of swinging the plates 10 to a vertical position, the operating shaft 8 is provided at one end with a vertically extending operating lever 12. This lever 12 is provided with an aperture 13 adjacent its upper end through which the cable 14 passes. This cable 14 is provided with knots 15 upon each side of the lever 12 as disclosed in Fig. 4. In this manner it will be seen that when the cable 14 is moved it will impart a swinging movement to the lever 12. This cable 14 is adapted to be operated by a station-master or other individual, or by any suitable controlling mechanism not deemed necessary to be herein disclosed. The end of the cable adjacent the track instrument passes around the pulley 16 carried by the pin 17 mounted upon the track 20 18 which is supported by one of the ties 3.

When the instrument is not in use it will normally assume the position indicated in full lines in Fig. 2. However, when it is desired to swing the plates to a vertical position for engagement by the valve operating mechanism of an engine, the cable will be pulled and will pass around the pulley 16 so as to swing the lever 12 of a vertical position which will in turn impart rotary motion to 25 the shaft 8 which will swing to a position indicated in dotted lines in Fig. 2 at which time the same is in position for use.

Inasmuch as the valve operating mechanism of the engine will strike one of the 30 plates with considerable force it is well to provide some means for locking the same in a vertical position, and thus prevent the plates from being swung or moved independently of the cable. Accordingly, the 35 operating shaft 8 is provided at the opposite end from the lever 12 with a vertical finger 19 which passes into the casing 20 carried by the ties 3. A pivot pin 21 is carried by the casing 20 and supports the locking shoe 22, this locking shoe 22 being provided with bifurcated end 23 and with the solid end 24. When the plates 10 are swung to a vertical position this shoe 22 is swung so as to allow the vertical finger 19 to be 40 positioned between the bifurcated ends 23 whereby the operating shaft 8 will be held

against accidental rotary movement. For the purpose of operating this locking shoe 22 there is provided an auxiliary cable 25 which passes within the casing 20 and then 5 extends to the same operating position as the cable 14. This cable 25 is passed around the secondary pulley 26 positioned within the casing 20 for this purpose. A pivot shaft 27 is also carried within the casing 20 adjacent 10 the upper portion of the casing and above the shoe 22. This pivot shaft 27 is adapted to carry the bell-crank lever 28 so as to allow the bell-crank lever to freely pivot or swing upon the same. One arm of this lever 28 15 is secured to the cable 25 as shown at 29 while the opposite end of the lever 28 is attached to the solid end 24 of the shoe 22 by means of the connecting link 30. The lower portion of the casing 20 is provided 20 with a secondary pivot shaft 31 for supporting the bell-crank lever 32 which is also connected to the cable 25 as is shown at 33 and which is also connected to the solid end 24 of the shoe 22 by means of the connection 34. After the plates have been 25 swung to the operative position, the finger 19 will extend vertically, at which time the locking shoe 22 is swung into position to engage the same. To accomplish this the 30 cable 25 is moved in the direction indicated by the arrow in Fig. 6 at which time it will be seen that the bell-crank lever 28 will be swung to draw upwardly to the solid end 24 by means of the link 30, whereby the locking shoe 22 will be swung upon the member 21 whereby the vertical finger 19 will pass between the bifurcated ends. The device will then be held in a set position so that 35 when the valve operating mechanism of the engine strikes the same any tendency of the shaft 8 to rotate by means of the force imparted to the plates 10 is eliminated by the locking shoe 22. However, after the engine is positioned the cable is moved in the opposite direction to the direction indicated 40 by the arrow in Fig. 6 whereby the bell-crank lever 32 will be swung and will draw downwardly upon the solid end 24 by means of the connection 34 whereby the shoe will 45 be swung from engagement with the vertical finger 19 so as to allow the shaft 8 to be rotated for swinging the plates 10 from a vertical position.

From the foregoing description it will be 55 seen that a simple operating mechanism has been produced which is adapted to operate the valve mechanism of an engine and which is provided with an efficient locking means for holding the device in a set position, this locking means being so formed as to be efficiently operated as desired.

Having thus described the invention what is claimed as new, is:—

1. In a track instrument the combination 65 with an operating shaft, tripping plates

carried by said shaft, means for operating said shaft so as to swing said plates to a vertical position when desired, said shaft provided at one end with a vertical finger, and means engaging said finger for holding 70 said shaft in a set position whereby said plates may be held against accidental movement when desired.

2. In a track instrument the combination 75 with a shaft, said shaft adapted to be rotatably secured upon a track, a tripping plate secured to said shaft, means for swinging said shaft whereby the plates may be moved to a vertical position when desired, said shaft provided at one end with a vertical finger, a casing positioned about the vertical finger, a locking shoe pivotally secured in said casing, said locking shoe provided with a solid end, said locking shoe also provided with bifurcated ends, means 80 for operating said locking shoe whereby said locking shoe may be swung within said casing so as to allow said vertical finger to pass between the bifurcated ends thereof, for holding the vertical finger in a set position thereby holding the operating shaft 85 against accidental rotary movement when in use.

3. In a track instrument the combination 90 with an operating shaft, said shaft adapted to be rotatably supported upon a track, tripping plates carried by said shaft, means for operating said shaft whereby said plates may be swung to a vertical position when desired, a casing carried adjacent one end portion of said operating shaft, said operating shaft provided with an integral vertically extending finger, a locking shoe pivotally secured within said casing, said locking shoe provided with a bifurcated end, 100 said shoe also provided with a solid end, an operating cable passing within said casing, a bell-crank lever pivotally secured within said casing, a link attached to one portion of said bell-crank lever and to said solid end of said locking shoe, said operating cable also attached to said bell-crank lever for swinging the same within said casing, whereby said locking shoe may be swung within said casing for allowing said vertical finger to rest between said bifurcated end, whereby said operating shaft will be held in a set position, and means for automatically swinging said locking shoe from 105 engagement with said vertical finger.

4. In a track instrument the combination 110 with an operating shaft, said shaft adapted to be rotatably supported upon a track, tripping plates carried by said operating shaft, means for swinging said operating shaft, a casing positioned adjacent one end of said operating shaft, said operating shaft provided with a vertically extending finger, a locking shoe pivotally secured within said casing, said locking shoe provided with a 115

bifurcated end, a bell-crank lever pivotally secured within said casing at a spaced distance above said vertical finger, a secondary bell-crank lever positioned within said casing at a spaced distance above said locking shoe, an endless cable positioned through said casing, said cable attached to each of said bell-crank levers, the free ends of said bell-crank levers provided with connecting means attached to the free end of said locking shoe whereby said locking shoe may be swung to engage said vertical finger when the plates are swung to a vertical position

or may be swung from engagement therewith after allowing said operating shaft to be rotated, said locking plate adapted to be swung by said bell-crank levers which are adapted to be operated by said endless cable. 15

In testimony whereof we hereunto affix our signatures in presence of two witnesses. 20
